ATTORNEY

UNITED STATES PATENT OFFICE

FRANK WALLACE, OF FREEPORT, NEW YORK

WATER-CLOSET

Application filed April 17, 1929. Serial No. 355,766.

This invention relates to certain new and useful improvements in water closets and has for one of its objects to improve the flushing features thereof by providing a water jet 5 opening in the apron of the bowl at the overflow side of the goose neck to increase the siphoning action and effect complete emptying of the bowl.

A further object of the invention is to provide a water closet having a water flushing inlet communicating with lateral passages in the bowl body, one passage leading to the flushing rim of the bowl and the other passage leading directly to the soil outlet pipe 15 with ducts forming communication between the lower ends of the lateral water passages and the bottom of the bowl to supply fresh water to the bowl after the flushing operation.

Another object of the invention is to provide a water closet having a flushing rim in communication with a lateral passage in the bowl body supplied from a chamber in the body and another chamber in communication with another lateral passage in the bowl body 25 supplied with water from the first named chamber and having an outlet rearwardly of the bowl to create a partial vacuum or suction to empty the bowl.

With the above and other objects in view 30 that will become apparent as the nature of the invention is better understood, the same consists in the novel form, combination and arrangement of parts hereinafter more fully described, shown in the accompanying drawings and claimed.

In the drawing:—

Figure 1 is a vertical longitudinal sectional view taken on line 1—1 of Figure 2 showing the jet opening in the siphon apron of the 40 bowl;

Figure 2 is a horizontal sectional view taken on line 2—2 of Figure 1, showing the lateral water passages;

Figures 3 and 4 are detail sectional views 45 taken on lines 3—3 and 4—4 respectively on Figure 2; and

Figure 5 is a vertical cross-sectional view taken on line 5—5 of Figure 1, the same being partly broken away.

50 The water closet comprises a body portion

A and a bowl B and while the same may be constructed for mounting in various ways, the same is illustrated as a wall supported type having a rear flange C provided with openings 12 through which anchoring bolts 55 are extended. The bowl B is provided with a flushing rim D and is of the usual type comprising the trap and siphon outlet having the wall E and apron F.

The water supply for the bowl includes the 60 water supply control 1 discharging into the chamber 2, the water flowing from the chamber 2 through lateral passages in the body A. As shown in Figures 2 and 3, part of the water from the chamber 2 flows downwardly 65 through the passage 3 and under the lower end of the partition 3^a, then upwardly through the passage 3' to the chamber 3^b that is closed to the bowl, where the same outlets through the jet opening 3^a through the passage 70 G at the rear side of the overflow wall E to the soil outlet 10. The jet of water flowing through the opening 3^a falls upon the bottom of the soil outlet 10 and rises therein to the upper side of the soil outlet for closing the passage G and creating a partial vacuum above and rearwardly of the wall E for drawing over the wall, by suction, the contents of the bowl B. The wall E has a vertical jet opening 4 therein communicating with the 75 trap of the bowl B, a duct 3² forming communication between the lower end of the jet opening 4 and the lower ends of the communicating passages 3 and 3'.

The water from the chamber 2 also flows 80 downwardly through the lateral passage 5 at the other side of the body A, the water flowing under the lower end of the partition 5^a and upwardly through the passage 5' to be delivered to the flushing rim D of the bowl 90 B. The lower communicating ends of the passages 5 and 5' communicate with the jet opening 4 by a duct 3² so that water flowing through both lateral passages of the body A have portions delivered to the jet opening 4. 95

A duct 9 forms communication between the lower end of each lateral water supply passage and the trap of the bowl B constituting means for supplying a fresh quantity of 100 water to the bowl after a flushing operation,

the fresh water being delivered to the bowl from the bottom side thereof to insure the overflow of all contaminated water.

5 The top wall of the body A above the chamber 3^b is provided with a clean out hole 6 above the opening 3^a that is closed by a plug 7 rendered water-tight by the gasket 8, the plug 7 being removable to permit access to the passage G and soil outlet 10 for cleaning purposes.

10 When water is admitted to the chamber 2 by the control device 1, a part thereof is delivered through the passages 5 and 5' to the flushing rim D while water from the chamber 2 also flows to the passages 3 and 3' to be outletted directly through the passage G to the soil pipe 10. During the flow of water through the passages 5 and 5' and 3 and 3', a quantity thereof is delivered to 15 the duct 3^a to the jet opening 4 to increase siphoning action in the bowl trap, this action also being increased by the downflow of water through the opening 3^a in the bottom wall of the chamber 3^b, thereby assuring a complete emptying of the bowl during a flushing 20 operation. When the bowl has been completely emptied, due to siphoning action through the top, the water remaining in the chamber 2 will flow to the passages 3-3' and 5-5' and be delivered to the ducts 3^a and 9 through the trap of the bowl and rise therein to seek its level above the lower edge of the apron F as shown in Figure 1, the water failing to rise upwardly in the passages 3' 25 and 5' as the same will seek its level through the ducts 9. The ducts 9 may be used when it is desired to drain the bowl during cold weather or when the same is out of use, the water being forced from the bowl over the 30 wall E while the water in the passages 3-3' and 5-5' will flow from the passages through the ducts 9 into the bowl to be exited therefrom.

35 From the above detail description of the invention, it is believed that the construction and operation thereof will at once be understood, the construction of the bowl being such that traps are formed by the partitions 3^a and 5^a in each of the lateral passage ways, 40 which in addition to the trap in the bowl formed by wall E and apron F, three separate and distinct traps are formed to prevent any sewer gas from leaving the bowl. While there is herein shown and described the preferred embodiment of the present invention, 45 it is nevertheless to be understood that minor changes may be made therein without departing from the spirit and scope of the invention as claimed.

50 I claim:

1. In a water closet, a bowl having a flushing rim, a water receiving chamber in the bowl, lateral water passages in the bowl in communication with the chamber, a water jet in the bowl trap, and ducts forming com-

munication between the lower ends of the lateral water passages and jet.

2. In a water closet, a bowl having a flushing rim, a water receiving chamber in the bowl, lateral water passages in the bowl in communication with the chamber, a water jet in the bowl trap, ducts forming communication between the lower ends of the lateral water passages and jet, and ducts forming communication between the lower ends of the water passages and bottom of the bowl trap for refilling the bowl trap.

3. In a water closet, a bowl having a flushing rim, a water receiving chamber in the bowl, lateral water passages in the bowl in communication with the chamber, a water jet in the bowl trap, ducts forming communication between the lower ends of the lateral water passages and jet, and the upper wall of the closet having a clean out opening in direct communication with the entrance to the soil pipe forwardly of the water receiving chamber.

4. In a water closet, a bowl having a flushing rim, a water receiving chamber in the bowl, lateral water passages in the bowl in communication with the chamber, a water jet in the bowl trap, ducts forming communication between the lower ends of the lateral water passages and jet, ducts forming communication between the lower ends of the water passages and bowl trap, and the upper wall of the closet having a clean out opening in direct communication with the entrance to the soil pipe forwardly of the water receiving chamber.

5. In a water closet, a bowl having a flushing rim, water supply means for the bowl including lateral passages of U-formation in the bowl body, and ducts forming communication between the lower ends of the lateral passages and the bottom of the bowl trap.

6. In a water closet, a bowl, water supply means for the bowl, a main water trap, and lateral passageways for water, each having a trap at its lower end and separately communicating with the bottom of the main trap.

7. In a water closet, a bowl, water supply means for the bowl, a main water trap, lateral passageways for water, each having a trap at its lower end, and means for refilling the main trap forming communication between the main and lateral traps.

8. In a water closet, a bowl, water supply means for the bowl, a main water trap, lateral passageways for water, each having a trap at its lower end, and means forming communication between the main and lateral traps including ports directed downwardly from the lateral traps to the main trap.

9. In water closet, a bowl, a flushing rim, a water receiving chamber and a soil outlet, a lateral passage having a fall and rise between the chamber and rim, a second chamber separate from the rim with a lateral passage hav-

ing a fall and rise between the first and second chamber, and a drop jet opening in the second chamber over the soil outlet.

10. In a water closet, a bowl, a flushing rim, a water receiving chamber and a soil outlet, a lateral passage having a fall and rise between the chamber and rim, a second chamber separate from the rim with a lateral passage having a fall and rise between the first and second chamber, and a drop jet opening in the second chamber over the coil outlet rearwardly of the bowl trap.

11. In a water closet, a bowl, a flushing rim, a water receiving chamber and a soil outlet, a lateral passage having a fall and rise between the chamber and rim, a second chamber separate from the rim with a lateral passage having a fall and rise between the first and second chamber, and a drop jet opening in the second chamber over the soil outlet, the drop jet opening being in a plane below both chambers whereby retrograde flow through the lateral passages will pass to the second chamber and outlet through the drop jet opening to the soil outlet.

12. In a water closet, a bowl, a flushing rim, a water receiving chamber and a soil outlet, a lateral passage having a fall and rise between the chamber and rim, a second chamber separate from the rim with a lateral passage having a fall and rise between the first and second chamber, and a drop jet opening in the second chamber over the coil outlet rearwardly of the bowl trap, the drop jet opening being in a plane below both chambers whereby retrograde flow through the lateral passages will pass to the second chamber and outlet through the drop jet opening to the soil outlet.

13. In a water closet, a bowl having a flushing rim, a trap and a soil pipe, a pair of chambers, lateral passages, one forming communication between one chamber and the rim and the other forming communication between the two chambers, one chamber constituting the water supply and the other chamber outletting to the soil pipe.

14. In a water closet, a bowl having a flushing rim, a trap and a soil pipe, a pair of chambers, lateral passages, one forming communication between one chamber and the rim and the other forming communication between the two chambers, one chamber constituting the water supply and the other chamber outletting to the soil pipe, and said traps being of U-formation with a central portion forming a bottom trap.

15. In a water closet, a bowl having a flushing rim, a trap and a soil pipe, a pair of chambers, lateral passages, one forming communication between one chamber and the rim and the other forming communication between the two chambers, one chamber constituting the water supply and the other chamber outletting to the soil pipe, said traps being of U-formation with a central portion forming a

bottom trap, and ports directed downwardly from the lateral traps to the main trap.

16. In a water closet, a bowl having a flushing rim, a trap and a soil pipe, a pair of chambers, lateral passages, one forming communication between one chamber and the rim and the other forming communication between the two chambers, one chamber constituting the water supply and the other chamber outletting to the soil pipe, the water supply chamber being located in the upper end of the bowl whereby fresh water therein after the supply has been shut off gravitates to the main trap.

17. In a water closet, a bowl having a flushing rim, a trap and a soil outlet, a water receiving chamber in communication with the rim and a second water receiving chamber in communication with the first named chamber and soil outlet whereby back flow through the flushing rim will be delivered to the first and second chambers consecutively and then to the soil outlet.

In testimony whereof I affix my signature.

FRANK WALLACE.
